UNITED STATES PATENT OFFICE.

ADOLF E. FOHN, OF MONTGOMERY, ILLINOIS, ASSIGNOR TO AURORA STEEL PRODUCTS COMPANY, OF AURORA, ILLINOIS, A CORPORATION OF ILLINOIS.

DOOR-LATCH.

1,348,001.

Specification of Letters Patent. Patented July 27, 1920.

Application filed January 9, 1920. Serial No. 350,260.

To all whom it may concern:

Be it known that I, ADOLF E. FOHN, a former subject of the Emperor of Germany, now a formal declarant of intention to be 5 come a citizen of the United States, and a resident of Montgomery, in the county of Kane and State of Illinois, have invented certain new and useful Improvements in Door-Latches, of which the following is a 10 specification, reference being had to the accompanying drawings.

This invention relates to improvements in door-latches designed particularly for use in connection with sheet-metal doors such 15 as are employed for metal clothes-lockers and similar devices. It is common to provide such metal doors with an inturned longitudinal flange at its free edge—that is, the vertical edge portion that is not secured by 20 the usual hinges to the body of the locker or similar device—and to slidably secure a latch-carrying bar adjacent to such flange, the latches being rigidly affixed to the bar and moved up bodily with such bar to dis- 25 engage them from their respective keepers that extend across the plane of movement of the latches. In all such prior constructions, so far as I am aware, it is necessary to provide some movable means projecting 30 through the face of the door and having a connection with said sliding bar whereby said bar may be moved upward to effect a disengagement of the latches from their respective keepers. The leading object of my 35 invention is to provide a latch construction that, while employing the usual slide-bar and utilizing the weight of such bar to hold the latches in engagement with their keepers, will not require any device to project 40 through the door as a means for raising the bar,—the bar by my invention being automatically raised, with a consequent disengagement of the latches, simply by an outward pull upon a handle or knob fixedly se- 45 cured to the outer face of the door and having no engagement at all with any part of the bar or with the latches. Briefly stated, I accomplish this object by pivoting each latch (if more than one is employed, as will 50 usually be the case) to the said inturned marginal flange of the door at a point sufficiently below the lower edge of the hook of the latch that engages the lower edge of the keeper so as to cause the inner or hook end 55 of the latch to turn down and automatically

disengage itself from such keeper when the door is pulled outward,—the other end of the latch being suitably connected to the sliding bar so that such bar will be moved upward during the unlatching operation, 60 and immediately thereafter, by gravity return the latch to a position to again engage under its keeper when the door is closed.

In the drawings,—

Figure 1 is a vertical section, partly 65 broken away, through a metal locker and its door with my improved latching mechanism attached thereto;

Fig. 2 is an enlarged view in side elevation, and partly broken away, of the latch- 70 ing device, the view being taken from the opposite side of the device shown in Fig. 1, and showing in vertical section a portion of the door;

Fig. 3 is a cross-section taken at line 3—3. 75 of Fig. 1;

Fig. 4 is a cross-sectional view through the locker taken at line 4—4 of Fig. 1 and showing an edge view of one of the latches and the sliding bar with which its outer end 80 is loosely connected;

Fig. 5 is a cross-section taken at line 5—5 of Fig. 1, and

Fig. 6 is a perspective view of one of the latch devices and portions of the locker and 85 its door.

Referring to the several figures of the drawings,—10 indicates a portion of the body of a locker formed of sheet-metal, in the front of which is the door-opening, such 90 door-opening being surrounded by a comparatively heavy frame 11 formed as usual of angle-iron bars, to which frame the door is secured along one edge by hinges 12 as usual. The door is indicated by 13 and will 95 ordinarily be formed of a sheet of metal with inturned marginal flanges for strengthening or stiffening purposes as is common in this class of doors. As only that flange at the vertical edge opposite the hinges will 100 require to be mentioned hereinafter, I have applied only to it a reference numeral, to-wit 14. At 13^a is shown one of the usual ventilating slits in the door above which is a pressed out piece forming a shield 13^b for 105 such slit. Lying alongside of the inner face of the vertical flange 14 of the door is a slide-bar 15, it being movably retained in place by a number of suitable guides 17 se- 110 cured by spot welding or otherwise to the

inner face of the door. In former constructions it has been the common practice, so far as I am aware, to rigidly secure to this slide-bar the latches that, by engaging fixed keepers, hold the door in closed position. In this construction, however, the latches are not so affixed to the bar but have instead a loose or movable engagement with the bar as hereinafter pointed out.

10 The latches referred to are indicated by 18, the number to be employed varying with the height of the door. Each latch co-operates with a fixed keeper 19 projecting horizontally behind and across the flange 14 of 15 the door when the door is closed and serving as a stop for such door-flange to abut against. The keeper is formed of a piece of sheet-metal that is bent so as to provide an end portion for attaching to some portion 20 of the locker,—in the present construction such attaching portion being riveted to the inner face of the angle-iron frame 11. In the lower edge of the keeper is formed a notch 20 into which the upper edge of the 25 latch projects, as shown.

Each latch is preferably stamped from a heavy piece of sheet-metal, and at its rear portion—that is the part farthest from the face of the door—it is formed with an upwardly-projecting hook end, adapted to engage with the lower edge of the keeper, or more accurately speaking with reference to the particular construction here illustrated, with the end wall of the notch 20 that is 30 formed in such lower edge. The hook end portion is so shaped as to present a substantially straight edge adjacent to and parallel with the rear face of the keeper when the latch is in engagement with such keeper, as 35 clearly shown in Figs. 1 and 6. The latch is connected to the door flange 14 by a pivot 21, the latch, in the construction shown, lying, as best shown in Fig. 4, in the space between the flange 14 and the slide-bar 15. 40 At its forward end the latch is provided with a lateral extension 22 that connects it with the slide-bar, the connection, as shown, being accomplished through the provision of an opening 23 formed in the slide-bar 45 into which the extension projects. Such opening 23 is here shown as a notch in the edge of such bar and it is to be large enough to permit the necessary turning therein of the part 22 when the latch is rocked on its 50 pivot 21. It will be evident that with the construction of latch mechanism described the weight of the slide-bar will, when the latch is in engagement with its keeper, tend to retain it in such engagement, and in that 55 respect, broadly speaking, it does not differ from former constructions, but it does differ essentially from all such former constructions in that by my improvements the person opening the door does not have to 60 first positively raise the bar to release the 65

latch but can by a direct outward pull only on the knob or handle of the door effect such release of the latch from its keeper. This is made possible by so locating the pivot 21 of the latch that it is in a different horizontal plane from that portion of the edge of the keeper that the edge of the latch rests against. Thus the force of the outward pull on the door is transmitted from the pivot 21 in a diagonal direction with the effect of 70 causing such a turning of the latch as will draw its hook end away from the keeper. The slide-bar being connected to the other end of the latch, as described, will, of course, be moved up, but as soon as the disengagement of the latch has been effected it will drop by gravity and bring the latch into proper position to again engage its keeper when the door is closed. Of course a stop of some description should be provided to 75 limit the downward movement of the bar so that the latch will not be swung into a position that will prevent proper engagement with its keeper when the door is closed, and as one means of limiting such 80 movement I have shown (see Fig. 2) a lug 24 riveted or otherwise secured to the bar and extending out through a short slot 25 in the door, two oppositely-extending wings 26 serving to cover said slot at all times. In 85 the outer end of this lug 24 is an eye 27 adapted, when the latch is in engagement with its keeper, to register with another eye in the lower end of a fixed door-handle 28 through which eyes the hasp of a padlock 100 may be passed to hold the door locked in closed position.

The upper edge of the hook end of the latch is curved as shown so as to facilitate its passing the keeper when the door is being 105 closed, as will be understood.

By providing the lower edge of the keeper with the notch 20 provision is made for so interlocking the latch and its keeper that not only is the door held latched in place, 110 but when the door is locked it cannot easily be pried open by the insertion of a tool in the crack between the flange 14 and the frame 11 because the face of the latch striking against the side of the notch will hold 115 the latch against being forced from the keeper.

What I claim as my invention and desire to secure by Letters Patent, is—

1. The combination with a door, of a 120 pivoted latch thereon extending out from the body of the door at an angle thereto, a fixed keeper with the lower edge of which said latch engages when the door is closed, and vertically-sliding means carried by the 125 door for holding said latch normally forced up into engagement with the keeper when the door is closed.

2. The combination with a door, of a 130 pivoted latch thereon extending out from

the body of the door at an angle thereto, a fixed keeper with the lower edge of which said latch engages when the door is closed, and gravity-operated means slidably secured 5 to the door for holding said latch normally forced up into engagement with the keeper when the door is closed.

3. The combination of a door, latching mechanism on the door comprising a vertically movable bar and a latch pivotally attached to the door and projecting out from the body of the door at an angle thereto, and a fixed keeper for the latch to engage when the door is closed, said latch being in engagement with the bar to cause a positive upward movement of the bar when the latch is being turned on its pivot to disengage it from the keeper.

4. The combination of a door, latching mechanism on the door comprising a vertically-movable bar and a latch pivotally attached to the door and projecting out from the body of the door at an angle thereto, and a fixed keeper for the latch to engage when the door is closed, said bar having an opening and the latch having a lateral extension that projects into said opening to cause a positive upward movement of the bar when the latch is being turned on its pivot to disengage it from the keeper.

5. The combination with a door having an inwardly-directed marginal member at its free vertical edge, a bar slidingly mounted at one side of said marginal member, a latch pivotally secured to said member and projecting away from the body of the door at an angle thereto, said latch having a lateral projection extending through an opening in said bar, and a fixed keeper with the lower edge of which said latch normally engages when the door is closed.

6. The combination with a door, of latching means located wholly at the inside of the door comprising a latch pivotally connected 45 with the door and extending out at an angle therefrom, a fixed keeper with the lower edge of which said latch engages, the pivot

of the latch being in a different horizontal plane than the point of contact of the edges of the latch and keeper so that the latch 50 will turn on its pivot and be disengaged from the keeper upon an outward pull on the door, and a sliding bar on the door connected with that end of the latch nearest the door for normally holding the other end of 55 the latch forced up into engagement with the keeper when the door is in closed position.

7. The combination with a door, of a latch pivotally connected therewith and extending out at an angle therefrom, a keeper for the latch to engage with, the pivot of the latch being in a different horizontal plane than the plane in which is located the edge of the latch that is in contact with the 60 keeper when the door is closed, whereby an outward pull upon the door will disengage the latch, and a sliding bar carried by the door for thereafter returning the latch to a position to again engage its keeper when 70 the door is closed.

8. The combination of a door, a latch pivotally connected intermediate of its ends with the door, a vertically-movable bar carried by the door and connected with one end 75 portion of said latch and tending to normally force the other end of the latch upward, and a keeper with the under edge of which the latch engages when the door is closed.

9. The combination of a door, a latch pivotally connected intermediate of its ends with the door, a vertically-movable bar carried by the door and connected with one end portion of said latch and tending to 85 normally force the other end of the latch upward, a keeper with the under edge of which the latch engages when the door is closed, and means for limiting the downward movement of the bar to cause the latch to be held in position to engage said lower edge of the keeper.

ADOLF E. FOHN.
